UNITED STATES PATENT OFFICE.

JOHN KLEIS, OF ANN ARBOR, MICHIGAN, ASSIGNOR OF ONE-HALF TO THE KLEIS BEVERAGE COMPANY, OF ANN ARBOR, MICHIGAN, AND ONE-HALF TO THE C. E. KLEIS COMPANY, OF DUBUQUE, IOWA, A COPARTNERSHIP COMPOSED OF HARRY A. KLEIS, WILLIAM KLEIS, HERMAN KLEIS, LEWIS E. KLEIS, LAURA M. KLEIS, AND IDA M. KLEIS.

DESIGN FOR A BOTTLE.

Application filed April 30, 1928. Serial No. 17,517. Term of patent 14 years.

To all whom it may concern:

Be it known that I, JOHN KLEIS, a citizen of the United States of America, residing at Ann Arbor, in the county of Washtenaw and State of Michigan, have invented a new, original, and ornamental Design for Bottles, of which the following is a specification, reference being had to the accompanying drawing, forming a part thereof.

Fig. 2 is a top plan view of the bottle.

I claim:

The ornamental design for a bottle, as shown.

JOHN KLEIS.
